DISCONNECT TYPE OF ELECTRIC SWITCH
Joseph Bernatt, Elmhurst, and Oscar B. Alsaker, Bellwood,
Ill., assignors to James R. Kearney Corporation, St.
Louis, Mo., a corporation of Delaware
Filed April 16, 1962, Ser. No. 187,549
10 Claims. (Cl. 200—48)

This invention relates to improvements in a disconnect type of electric switch of the kind shown in the patent to Froland, 2,303,119, and more particularly to an enclosed shunt connection between the movable blade and the fixed part of the hinge mounting for the blade. It will be readily recognized that unless such a shunt is provided, the electric circuit would include the hinge bearings and the bearings on which the blade turns and that such bearings ordinarily offer poor contact area for heavy current loading. For this reason, a shunt connection has been used to carry the heavy current around the bearings of the mechanical joints in switches to improve the service life of the bearings and reduce the voltage drop. At first pigtails of flexible stranded wire were used, such as in Froland, but service conditions soon proved them not entirely satisfactory, and, as service conditions have a tendency to become more demanding and maintenance more costly, the standards for a marketable product rise. Consequently, it is now required that a product of this kind to be saleable must have certain features to increase its efficiency and prolong its service free life. The instant invention has proved features which make it outstanding in these respects.

It is an object of this invention to provide a blade hinge structure for a switch with a shunt connection around the hinge structure which is fully enclosed to provide a weather proof construction for protection against oxidation whereby maintenance is reduced.

It is another object of this invention to provide a blade hinge structure for a switch with a separate electrical shunt which avoids current transfer function in the mechanical bearings for the hinge.

It is another object of this invention to provide a blade hinge structure of a switch with an electrical shunt connection separate from the hinge and which provides for a straight line current path without offsets which will set up magnetic forces tending to relieve contact pressure.

It is another object of this invention to provide a blade hinge structure of a switch with a separate electric shunt connection providing an electrical configuration that will increase contact pressure with increases in current or load.

It is a further object of this invention to provide a combined blade hinge structure and a rotary blade mounting structure for a switch to connect the blade directly with a stationary conducting part of the hinge mounting, which shunt connection is fully enclosed and protected.

It is another object of this invention to provide a combined blade hinge structure and separate electric shunt connection between the switch blade and a stationary conducting part of the hinge mounting which is fully enclosed and constructed to function separately without interference to hinge movement.

It is still another object of this invention to provide a combined blade hinge structure and rotary blade mounting for a switch with a separate electric shunt to connect the blade directly with a stationary conducting part of the hinge mounting, which shunt is fully enclosed and protected and is capable of full floating or self-centering action to function separately without interference with, or interference from, the hinge or blade movement in its mechanical bearings.

2

Further objects and advantages of this invention will appear from the following detailed description which is in such full, clear and exact terms as will enable any person skilled in the art to make and use the same when taken in conjunction with the accompanying drawings, 5 forming a part thereof, and in which:

FIG. 1 is an environmental view in side elevation of one form of disconnect switch to which this invention is applicable;

FIG. 2 is a top view with parts broken away and in section of the blade hinge construction shown in FIG. 1 and illustrated in FIG. 2 on an enlarged scale;

FIG. 3 is a side view of the hinge shown in FIG. 1 with parts broken away and in section illustrating the blade hinge structure on an enlarged scale;

FIG. 4 is a top plan view illustrating the housing shown in FIG. 1 on an enlarged scale;

FIG. 5 is a front elevational view partly in section of the housing shown in FIG. 4;

FIG. 6 is an exploded view in top plan with parts in section illustrating the parts forming the electric shunt connection for the blade hinge shown in FIG. 2;

FIG. 7 is a front view of the blade contact part of the shunt connection shown in top plan in FIG. 6;

FIG. 8 is a view in elevation illustrating the outer end of the hinge contact trunnion of the hinge shown in FIG. 2 on an enlarged scale;

FIG. 9 is a view in elevation of the inner end of the trunnion shown in FIG. 8;

FIG. 10 is a side elevational view partly in section illustrating the castle type threaded plug for holding the blade of the switch; and

FIG. 11 is a fragmentary view, partly in section taken on the line 11—11 looking in the direction of the arrows.

Referring now to the above briefly described figures of the drawing and FIG. 1 in particular, the disconnect switch elements shown include a base 1 of channel iron of suitable dimensions. Bolted to the channel iron 1 at spaced points are a pair of brackets 2 and 3 secured to the channel iron by bolts 4 and 5, respectively. Each of these brackets in turn supports an insulator member, such as 6 and 7, held to the top of the brackets 2 and 3, respectively, by fastening means 8 and 9. At the top end of the insulator 6 is a fitting 12 secured thereto by suitable bolts, not shown. This fitting includes a terminal extension 14, the upper side of which is recessed at 16 and provided with bolt holes to receive, and a means to secure, a conductor between a clamping plate and terminal 14. The fitting 12 also has bolted thereto a pair of spaced spring type contacts 24 secured in place by bolts 26. These spring type fixed contacts are biased in a direction toward one another so as to clamp the movable end of a switch blade, such as 29, all in a well known manner. Both contacts are identical and the free ends thereof are bent upon themselves in the form of a U so as to provide a slot into which the end 36 of the movable blade 29 is wedgingly engaged. The fitting 12 also carries a small extension 38 mounting a stop screw 40 which limits the movement of the end 36 of the switch blade 29 in a switch closing direction.

The insulator 7 carries a bracket 11 by means of a pair of struts, such as 13, integral with a circular base 15 which is in turn secured to the top of the insulator 7 by bolts, such as 16. Struts 13 extend upwardly from the base 15 to a pair of hollow boss members 23 and 25, respectively. From this view, it will be apparent that the bracket 11 forms the stationary support for the hinge bearings mounting the switch blade 29 of the disconnect switch mechanism. Also referring to FIG. 1, the bracket 11 carries a small extension projecting horizontally therefrom which has a threaded aperture to receive a stop

screw 33 locked in position by a suitable stop nut. Whereas, the two insulators 6 and 7 heretofore described are mounted on fixed mountings in a fixed position with respect to the base 1, nevertheless, the base or the mountings can be reversed so that the switch is mounted in an inverted position. This is likewise true of the insulator 45, which is supported on a flange 46 rotatable with the vertically mounted shaft 50. Bolts 48 attach the insulator to the flange. Shaft 50 is rotatably mounted in a bearing support member 52 secured to the channel member 1 by bolts 54 and 56. Bolt 56 also anchors in position a bracket 57 carrying an adjustable stop bolt 59. The stop bolt 59 is aligned with the end of a short arm 69 (FIG. 11) turning with the shaft 50 and limits the rotary motion of the shaft 50 in one direction. One end of the shaft 50 projects below the base 1 and has a projecting end 61. Any form of actuating linkage may be connected to end 61 to turn the shaft 50. At the top of the insulator 45 is a crank 64 suitably secured by a plurality of bolts, such as 66 and 67, to the upper end of the insulator 45. The end of crank 64 is pinned to a clevis 69 which is rotatable within a boss of forked bracket 70. The branched arms of the bracket 70, indicated as 72 and 74, straddle the upper ends 76 of a control arm rigidly secured to the switch blade 29. A pin 75 forms the rotatable connector between the spaced arms 72 and 74 of the bracket 70 and the control arm 76. Control arm 76 is formed as a part of a sleeve 78 through which the switch blade passes, which sleeve is secured in place by a bolt 79.

Crank 64 has a bearing part, indicated generally as 80, journaled in an aperture within a bracket 82. On the upper surface of the bracket 82 is a recess 84 with suitable bolt holes 85 and 86. The bracket 82 forms the other terminal to receive the other conductor which can be secured in the recess 84 by a suitable clamp held against the bracket 82 by bolts passing through the apertures 85 and 86. This description so far has been confined to the basic elements of a known type of switch of the type in which the contact arm, or blade, 29 can pivot both on its own axis and on a hinge mounting during its opening and closing action. This hinge mounting, to be herein-after described in detail, includes both mechanical parts supporting the switch blade 29 for the aforesaid motion and also electrically connected parts, herein termed a shunt, forming an electrical connection between the blade 29 and the bracket 11.

Turning now to FIGS. 2 and 3, the bosses 23 and 25 supported by the struts 13 and bracket 11 are hollow and receive therein trunnions 90 and 91. Trunnion 90 is mounted in the boss 23 and trunnion 91 in the boss 25. These trunnions are shown in detail in FIGS. 6, 8 and 9. Since both are identical, only one will be described. The trunnion 90 in FIG. 8 is provided with a threaded bore 93 extending inwardly of the trunnion from its outer end. This portion of trunnion 90 containing bore 93 has a plurality of fingers separated by radial slots, indicated as 97, so that the finger portion 95 may be expanded for a purpose herein-after described. The finger portion 95 forms a continuation of a bearing portion 96 located between opposite ends of trunnion 90. The inner end of the trunnion 90 has a plurality of concentric flexible fingers 99. These are formed by radial slots cut in a sleeve extension from the trunnion 90. At the outer ends of these concentrically arranged fingers are circumferential grooves 100 and 101 to receive separate garter springs.

FIG. 6 shows a tapered plug 103 provided on its exterior with a tapered pipe thread and at its outer end with a socket 104 to receive a wrench. The threads 105 are sized to mate with the threads in the socket 93 of the trunnion 90. Returning now to FIG. 2, the trunnion 90 is placed within the hollow boss 23 and anchored therein by the expanding action of the threaded plug 103 in the socket 93 of the trunnion, which, when screwed in by a suitable wrench engaging the socket 104, causes the fingers

5 on portion 95 of the trunnion to expand anchoring it solidly in the boss 23. The boss 25 is also fitted with trunnion 91 in the same manner. The bearing portion 96 of the trunnions 90 and 91 forms the support for the hinge structure supporting the blade 29.

10 There is provided a tubular housing 110, best shown in FIGS. 4 and 5. The tubular housing 110 has a pair of radial extensions 112 and 114, both of which are provided with hinge bearings on the internal surfaces 116 and 117 located internally of the radial extensions 112 and 114. One of these radial extensions has formed integrally therewith a stop finger 118. On the tubular housing 110 are a pair of bearing surfaces 119 and 120 for the rotatable support of the blade.

15 Returning now to FIGS. 2 and 3, the tubular housing 110 has its radial extensions 112 and 114 journaled on the bearing part 96 of each trunnion 90 and 91. Surfaces 116 and 117 form bearing parts for the hinge. Thus, the housing 110 is free to swing in one direction towards switch closing position an amount permitted by the stop screw 49 and in the switch opening direction to a position fixed by contact between the stop finger 118 and the stop screw 33.

20 As heretofore mentioned, the sleeve 78 is fixed to the blade 29, and this sleeve in turn has a cylindrical bearing surface 122 which extends into the housing 110 and is journaled on the cylindrical bearing surface 119.

25 Turning now to FIGS. 2 and 10, the castle type threaded plug 125 has a cylindrical extension 130 dimensioned to form a bearing support on the bearing surface 120 of the housing 110. A flange 128 has a radial part which abuts the face of the bearing 120 and prevents end-wise movement. On the flange 128 is a bevelled face 129 with a cone angle of about 30° and the projecting hexagonal crown 126 is provided with slots, all in a conventional manner.

30 Returning now to FIGS. 2 and 3, the blade 29 clamped in the collar 78 is supported for rotation on the bearing part 122 within the housing 110. The end of the blade 29 is threaded to receive the castle nut 125 which also has a bearing surface 130, heretofore described, supported within the bearing surface 120 of the housing 110. The castle nut 125 is locked in place by a bolt 135 projecting through radial slots in the crown of the castle nuts 125 and through aligned holes in the tubular blade 29. Thus, the mechanical hinge for the blade 29 is formed by the housing member 110 pivotally supported on the trunnions 90 and 91 and in turn rotatably supports the blade 29 for turning about its axis in the bearing surfaces 119 and 120. The housing 110 is also sealed at these bearing points by a plurality of separate O-rings. The rings 137 and 138 seal the joint between the housing 110 and the bosses 23 and 25. The O-rings 139 and 140 seal the joint between the housing and its rotatable journals for the blade 29. From what has been heretofore described, it will be recognized that the housing 110 forms the movable part of the hinge structure, while the bosses 23 and 25 form the fixed mounting, or support, for the hinge structure. The housing 110 also forms the rotatable bearing for the blade 29. These are the mechanical connections which permit the blade to hinge with respect to the switch and for the blade 29 to rotate axially to release its beaver tail end 160 from between the fixed contacts 24 of the switch. This mechanical connection for the hinge and the blade is entirely separate from, and isolated from, any current carrying function. The current carrying function from the blade 29 to the bracket 11 carrying the terminal 84 is entirely separate from the mechanical connection and enclosed within the housing 110.

35 As heretofore described, the trunnions 90 and 91 carry a plurality of concentrically arranged contact fingers, or brushes, 99, and the current transfer from the bracket 11 is directly to the trunnions 90 and 91 which are stationary within the bosses 23 and 25. Plugs 103 produce an expanding ac-

tion on the portions 95 of the trunnions, expanding these radial fingers so as to form a high pressure connection between the interior of the bosses 23 and 25 and the exterior of the resilient portions 95 of the trunnions 90 and 91. As will be seen from inspection of FIGS. 2 and 3, the electric current path is from the trunnions to the fingers or brushes 99 and from there to a fitting 145. This fitting is better shown in FIGS. 6 and 7. Turning now to these latter mentioned figures, the fitting 145 is a hollow sleeve, or tubular sleeve, of a size to rotatably receive the end of the blade 29. The fitting has a collar 148 and integrally connected brushes, or fingers, 149 which are arranged concentrically of the blade 29. The ends of the fingers 149 are grooved at 150 and 151 so as to receive a pair of garter springs. Projecting radially from the collar 148 are a pair of cylindrical pins 153 and 154 which have an outside dimension of a size to be slidably and rotatably received within the fingers 99 on the trunnions 90 and 91. Returning now to the views in FIGS. 2 and 3, the fitting 145 is telescoped over the end of the blade 29 with its fingers 149 projecting into the tubular housing 110 adjacent the fixed collar 78. The fingers 149 are held in snug engagement with the exterior of the blade surface by a pair of garter springs 155 received in the grooves 150 and 151. These springs resiliently force the brushes, or fingers, 149 into engagement with the exterior of the tubular blade 29 forming a firm electric contact therewith. If desired, the exterior of the blade 29 at the point of contact mentioned may be provided with a contact ring of conducting material upon which the fingers 149 may bear. The springs 155 produce a high pressure contact between the inside of the fingers 149 and the area on the blade 29 opposed thereto. Similarly, the pins 153 and 154 are received within the flexible fingers, or brushes, 99 of the trunnions 90 and 91, and these fingers are urged into high pressure contact with the pins by pairs of garter springs 156 and 157. Thus, the path of current flow is through the bracket 11 into the trunnions 90, fingers 99, pins 153 and 154, fingers 149 and blade 29. This forms the shunt connection between the blade and the bracket 11 which will carry the electric current. This shunt connection, just described, is entirely separate from the mechanical bearing support for the blade. It is a straight line connection and one in which magnetic forces due to heavy current merely cause the fingers, or brushes, 99 and 149 to grasp their contact surfaces more firmly, thus, increasing the efficiency of this electric connection. The shunt connection itself is entirely enclosed within the tubular housing 110 and its radial extensions, it, therefore, may be treated with corrosion inhibiting substance sealed within the housing 110. This housing forms a weather-proof construction to eliminate contact oxidation and reduce maintenance. The shunt connection itself is one which will provide full contact regardless of blade position. Magnetic forces would not act in this shunt contact to relieve contact pressure, but on the other hand magnetic forces, if present, would tend to increase contact pressure. In this shunt connection, the blade 29 may not only rotate with respect to the fitting 145, but it is also possible for the fitting 145 to adjust its position lengthwise of the blade so as to accommodate its position with any eccentricity in the mechanical bearing support for the hinge. It is also a feature of this shunt connection that the pins 153 and 154 cannot only rotate within the fingers, or brushes, 99, but also slide endwise therein. These two features of the shunt connection provide for a self-centering action, or full floating connection, which cannot bind and restrict the operation of the mechanical bearing support for the blade 29.

The switch is operated through the fitting 61 by any suitable operating linkage. If the switch is closed and it is desired to open it, the linkage is moved to rotate the fitting 61 and crank 64. This in turn will twist the blade 29 to a position where the pressure of contacts 24 is relieved from

the edges of the beaver tail 160. During this movement, contact is maintained through the shunt by the action of the brushes, or fingers, on the fitting 145 which are held firmly in contact with the outer surface of the blade 29 as it rotates in its bearings 122 and 120. Further rotation of the crank 64 by the fitting 61 swings the blade 29 vertically about its hinge bearings 116 and 117 in the housing 110. During this movement, the shunt contact is maintained by the fingers 99 gripping the pins 153 and 154. At no time will there be a substantial current flow through the mechanical bearings of the hinge, or the blade, since the shunt connection within the housing 110 is effective continuously during any blade movement. The surfaces of the blade adjacent the fingers 149 and the surfaces of the pins 153 and 154 adjacent the fingers 99 and gripped thereby are maintained free of corrosion with an inhibitor grease. Leakage into the housing 110 is resisted by the O-rings 137, 138, 139 and 140. Closing of the switch is effected by reverse movement of the crank 64 which produces a reverse sequence of operation in the blade 29.

Changes in and modifications of the construction described may be made without departing from the spirit of our invention or sacrificing its advantages.

Having thus described the invention, what is claimed and desired to be secured by Letters Patent is:

1. In a disconnect type of electric switch having in combination, (1) a fixed contact, (2) a switch blade, and (3) a housing enclosing one end of said switch blade and rotatably mounted on a fixed bearing part on said switch which projects into said housing to form a hinge upon which said housing and blade are free to swing to move the other end of said switch blade into and out of contact with said fixed contact and in which said blade is journaled for rotation about its axis, the improvement in said combination comprising,

(a) an electrical shunt connection between said blade and said fixed bearing part within said housing including electric conductor means, one of which has a plurality of cylindrically arranged spring biased fingers and the other of which is a pin gripped in said fingers and axially and rotatably movable in said fingers, said means being substantially coaxial with said hinge and in said housing and one of said means being separately and slidably connected with said blade for relative rotary movement with said blade as said blade swings and relative axial movement on said blade to obtain a self-centering action between said pin and said fingers as said blade swings on said hinge.

2. In a disconnect type of electric switch having in combination, (1) a fixed contact, (2) a switch blade, and (3) a housing enclosing one end of said switch blade and a rotatable mounting on a fixed bearing part on said switch which projects into said housing to form a hinge upon which said housing and blade are free to swing to move the other end of said switch blade into, and out of, contact with said fixed contact and in which said blade is journaled for rotation about its axis, the improvement in said combination comprising,

(a) an electrical shunt connection between said blade and said fixed bearing part within said housing including electric conductor means one of which has a rotatable electric connection with said mounting movable in a direction at right angles to said blade and the other of which has a rotatable electric connection with said blade in which said blade is rotatable and axially movable in a direction at right angles to said hinge between said fixed bearing part and said housing to form a self-centering connection between said electric conductor means and said mounting as said blade swings on said hinge.

3. In a disconnect type of electric switch having a fixed contact, a movable blade mounted to swing into and out of contact with said fixed contact, a mounting for said movable blade, and a hinged connection between said

blade and said mounting, the improvement in said hinged connection comprising,

- (a) a relatively stationary hinge part with coaxial oppositely located spaced bearing surfaces on said mounting,
- (b) a generally tubular hinge part forming a housing,
- (c) bearings on said tubular housing for supporting said switch blade with a portion enclosed within said tubular housing,
- (d) bearing parts on said tubular housing journalled on said coaxial spaced bearing surfaces to form a mechanical hinged connection between said blade and said mounting,
- (e) and an electrical shunt connection between said blade and said hinge part including electric conductor means one of which has a plurality of cylindrically arranged flexible fingers and the other of which is a pin gripped by said fingers and axially and rotatably movable in said fingers, said means being substantially coaxial with said bearing surfaces of said hinge part and one of said means being separately and slidably connected with said blade for relative rotary movement with said blade as said blade swings and for relative axial movement on said blade to form a self-centering connection between said pin and fingers as said blade swings on said hinge part.

4. In a disconnect type of electric switch having a fixed contact, a movable blade mounted to swing into and out of engagement with said fixed contact, a mounting for said blade, and a hinge connection between said blade and said mounting, the improvement in said hinge connection comprising,

- (a) a relatively stationary hinge part with coaxial spaced separate bearing surfaces removably fixed in said mounting,
- (b) a generally tubular hinge part forming a housing extending at right angles to the coaxial spaced bearing surfaces and enclosing a portion of said hinge part,
- (c) spaced bearings on said tubular housing for rotatably supporting said switch blade with a portion enclosed within said tubular housing,
- (d) bearing parts on said tubular housing journalled on said separate bearing surfaces to form a mechanical hinge connection between said blade and said mounting,
- (e) and an electrical shunt connection between said blade and said stationary hinge part within said housing including electric conductor means one of which has a plurality of cylindrically arranged spring biased fingers and the other of which is a pin gripped in said fingers and axially and rotatably movable in said fingers, said means being substantially coaxially with said fixed bearing surfaces and one of said means being separately and slidably connected with said blade for relative rotary movement with said blade as said blade swings and relative axial movement on said blade to form a self-centering connection between said means as said blade swings on said hinged connection.

5. In a disconnect type of electric switch having a fixed contact, a movable blade mounted to swing into and out of engagement with said fixed contact, a mounting for said blade and a hinge connection between said blade and said mounting, the improvement in said hinged connection comprising,

- (a) a relatively stationary hinge part with coaxial spaced, separate bearing surfaces removably fixed in said mounting,
- (b) a generally tubular hinge part forming a housing,
- (c) spaced bearings on said tubular housing for rotatably supporting said switch blade with a portion enclosed within said tubular housing,
- (d) bearing parts within said tubular housing journalled on said coaxial, spaced, separate bearing surfaces to form a mechanical hinge connection for said blade and housing on said mounting,

(e) and an electrical shunt connection between said blade and said stationary hinge part within said housing including electric conductor means having a rotatable electric connection with said mounting movable in a direction at right angles to said blade and a plurality of concentrically arranged spring biased fingers surrounding and gripping said blade in which said blade is rotatable and also axially movable in a direction at right angles to said hinge connection to form a self-centering connection between said electric conductor means and said mounting as said blade swings on said stationary hinge.

6. In a disconnect type of electric switch having a fixed contact, a movable blade mounted to swing into and out of engagement with said fixed contact, a mounting for said blade, and a hinged connection between said blade and said mounting, the improvement in said hinge connection comprising,

- (a) relatively stationary trunnions with coaxial spaced separate bearing surfaces removably fixed in said mounting,
- (b) a generally tubular hinge part forming a housing extending at right angles to the axis of said trunnions and enclosing a portion thereof,
- (c) spaced bearings in said tubular housing for rotatably supporting said switch blade with a portion enclosed within said tubular housing,
- (d) bearing parts in said tubular housing journalled on said trunnions to form a mechanical hinge connection between said blade and said mounting,
- (e) and an electrical shunt connection between said blade and said trunnions within said housing including electric conductor means one of which has a plurality of cylindrically arranged spring biased fingers and the other of which is a pin gripped by said fingers and axially and rotatably movable in said fingers, said means being one of said means being substantially coaxially with said trunnions and separately and slidably connected with said blade for relative rotary movement with said blade as said blade swings and relative axial movement on said blade to form a self-centering connection between said means as said blade swings on said hinge connection.

7. In a disconnect type of electric switch having a fixed contact, a movable blade mounted to swing into and out of engagement with said fixed contact, a mounting for said blade and a hinge connection between said blade and said mounting, the improvement in said hinge connection comprising,

- (a) relatively stationary trunnions with coaxial spaced, separate, bearing surfaces removably fixed in said mounting,
- (b) a generally tubular hinge part forming a housing extending at right angles to the coaxially spaced trunnions and enclosing a portion of said trunnions,
- (c) spaced bearings in said tubular housing for rotatably supporting said switch blade with a portion enclosed within said tubular housing,
- (d) bearing parts in said tubular housing journalled on said trunnions to form a mechanical hinge connection for said blade and housing on said mounting,
- (e) and an electrical shunt connection between said blade and said trunnions within said housing including electric conductor means one of which has a rotatable electric connection with said mounting movable in a direction at right angles to said blade and the other of which has a plurality of concentrically arranged spring biased fingers surrounding and gripping said blade in which said blade is rotatable and also axially movable in a direction at right angles to said hinge connection to form a self-centering connection between said electric conductor means and said mounting as said blade swings on said hinge connection.

8. In a disconnect type of electric switch having a fixed contact, a movable blade mounted to swing into and out of engagement with said fixed contact, a mounting for said blade and a hinge connection between said blade and said mounting, the improvement in said hinge connection comprising,

- (a) spaced, coaxial, hollow boss parts on said mounting,
- (b) relatively stationary trunnions with hollow expandable and contractible end portions slidable into said hollow boss parts on said mounting,
- (c) plug means adapted to expand said hollow expandible end portions in said hollow boss parts to obtain a high pressure electrical connection between said hollow boss parts and said trunnions,
- (d) a generally tubular hinge part forming a housing extending at right angles to said trunnions and enclosing a portion of said trunnions,
- (e) spaced bearings in said tubular housing for rotatably supporting said switch blade with a portion enclosed within said tubular housing,
- (f) bearing parts in said tubular housing journaled on said trunnions to form a mechanical hinge connection for said blade and housing on said mounting enclosing an expandible contractible portion of said trunnions,
- (g) and an electrical shunt connection between said blade and said mounting within said housing including electric conductor means one of which has a plurality of cylindrically arranged spring biased fingers formed by the expandible contractible portion of said trunnions enclosed in said housing and the other of which is a pin gripped by said fingers and axially and rotatably movable in said fingers, said means being substantially coaxially with said trunnions and one of said means being separately and slidably connected with said blade for relative rotary movement with said blade as said blade swings and relative axial movement on said blade to form a self-centering connection between said means as said blade swings on said hinge connection.

9. In a disconnect type of electric switch having a fixed contact, a movable blade mounted to swing into and out of engagement with said fixed contact, a mounting for said blade, and a hinge connection between said blade and said mounting, the improvement in said hinge connection comprising,

- (a) spaced, coaxial, hollow boss parts on said mounting,
- (b) relatively stationary trunnions with hollow expandible and contractible end portions slidable into said hollow boss parts on said mounting,
- (c) plug means adapted to expand said hollow expandible end portions in said hollow boss parts to obtain a high pressure electric connection between said hollow boss parts and said trunnions,
- (d) a generally tubular hinge part forming a housing extending at right angles to said trunnions and enclosing a portion of said trunnions,
- (e) spaced bearings in said tubular housing for rotatably supporting said switch blade with a portion enclosed within said tubular housing,
- (f) bearing parts in said tubular housing journaled on said trunnions to form a mechanical hinge connection for said blade and housing on said mounting enclosing an expandible contractible portion of said trunnions,

ing an expandible contractible portion of said trunnions,

(g) and an electrical shunt connection between said blade and said mounting within said housing including electric conductor means, one of which has a rotatable electric connection with said mounting movable in a direction at right angles to said blade and the other of which has a rotatable electric connection with said blade in which said blade is rotatable and axially movable in a direction at right angles to said hinge connection to form a self-centering connection between said electric conductor means and said mounting as said blade swings on said hinge connection.

15 10. In a disconnect type of electric switch having a fixed contact, a movable blade mounted to swing into and out of engagement with said fixed contact, a mounting for said blade, and a hinge connection between said blade and said mounting, the improvement in said hinge connection comprising,

- (a) spaced, coaxial, hollow boss parts on said mounting,
- (b) relatively stationary trunnions with hollow expandible and contractible end portions slidable into said hollow boss parts on said mounting,
- (c) plug means adapted to expand said hollow expandible end portions in said hollow boss parts to obtain a high pressure electric connection between said hollow boss parts and said trunnions,
- (d) a generally tubular hinge part forming a housing extending at right angles to said trunnions and enclosing a portion thereof,
- (e) spaced bearings in said tubular housing for rotatably supporting said switch blade with a portion enclosed within said tubular housing,
- (f) bearing parts in said tubular housing journaled on said trunnions to form a mechanical hinge connection for said blade and housing on said mounting and enclosing an expandible contractible portion of said trunnions,
- (g) and an electrical shunt connection between said blade and said mounting within said housing including electrical conductor means, one of which has a plurality of concentrically arranged spring biased fingers formed by the expandible contractible portion of said trunnions and the other of which has a plurality of concentrically arranged spring biased fingers surrounding and gripping said blade in which said blade is rotatably and axially movable in a direction at right angles to said hinge connection, oppositely extending pins integral with said last-mentioned spring biased fingers gripped by the fingers on said trunnions and axially and rotatably movable in said fingers to form a self-centering connection between said blade and mounting as said blade swings on said hinge connection.

UNITED STATES PATENT OFFICE
CERTIFICATE OF CORRECTION

Patent No. 3,192,332

June 29, 1965

Joseph Bernatt et al.

It is hereby certified that error appears in the above numbered patent requiring correction and that the said Letters Patent should read as corrected below.

Column 8, line 37, strike out "one of said means being" and insert the same after "and" in line 38, same column 8.

Signed and sealed this 15th day of March 1966.
